US0D1013873S

(12) **United States Design Patent** (10) **Patent No.:** **US D1,013,873 S**
(45) **Date of Patent:** **** Feb. 6, 2024**

(54) **PROPHY ANGLE BODY**

(71) Applicant: **Young Dental Manufacturing I, LLC**,
Earth City, MO (US)

(72) Inventor: **Chevis Watkinson**, Appleton, WI (US)

(73) Assignee: **Young Dental Manufacturing I, LLC**,
Earth City, MO (US)

(**) Term: **15 Years**

(21) Appl. No.: **29/843,102**

(22) Filed: **Jun. 17, 2022**

(51) LOC (14) Cl. **24-02**

(52) U.S. Cl.

USPC **D24/176**

(58) **Field of Classification Search**

USPC D24/152, 176-180

CPC A61C 17/005; A61C 17/16; A61C 1/12

See application file for complete search history.

(74) *Attorney, Agent, or Firm* — McDermott Will and Emery LLP

(57) **CLAIM**

The ornamental design for a prophy angle body, as shown and described.

DESCRIPTION

FIG. 1 is a perspective view of a prophy angle body;

FIG. 2 is another perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a back view thereof;

FIG. 9 is a perspective view of a prophy angle body in another example of the design;

FIG. 10 is another perspective view thereof;

FIG. 11 is a left side view thereof;

FIG. 12 is a right side view thereof;

FIG. 13 is a top view thereof;

FIG. 14 is a bottom view thereof;

FIG. 15 is a front view thereof; and,

FIG. 16 is a back view thereof.

The broken lines represent unclaimed subject matter and form no part of the claimed design.

1 Claim, 12 Drawing Sheets
